BOILER CLEANER

Application filed August 11, 1930. Serial No. 474,483.

My invention relates to new and useful improvements in boiler cleaners and is designed specifically for use in that class of boiler cleaners by means of which a cleaning fluid is discharged against the surfaces to be cleaned.

One of the objects of my invention is to provide a rotary boiler cleaner in which the cleaning fluid will be supplied to the cleaner just before the cleaner begins the cleaning rotation. Another object is to provide such a cleaner in which the valve will be open during the entire cleaning rotation or rotations of the cleaner. Other objects will appear hereinafter. The invention consists in the combinations and arrangements of parts herein described and claimed.

The invention will be best understood by reference to the accompanying drawings forming a part of this specification and in which:

Figure 1 is a front elevational view of the invention;

Figure 2 is a side elevation of the invention;

Figure 3 is a central vertical sectional view of the head and valve used in the invention;

Figure 4 is a central sectional view of a cap used in the invention;

Figure 5 is a sectional view of a valve used in the invention taken substantially on line 5-5 of Figure 6;

Figure 6 is a horizontal central sectional view of a valve used in the invention;

Figure 7 is an end elevational view partly in section of a boiler cleaner showing a slightly modified form of construction;

Figure 8 is a sectional view taken substantially on the line 8-8 of Figure 7;

Figure 9 is a vertical sectional view showing a still further modified form of construction;

Figure 10 is a sectional view taken substantially on the line 10-10 of Figure 9; and

Figure 11 is a detail sectional view taken substantially on the line 11-11 of Figure 9.

The preferred form of construction consists of a blower unit or perforated pipe 10 which is swivelly mounted in a head 11.

Rigidly mounted upon the member 10 adja-

cent the end which is positioned within the head 11 is a gear 12 which meshes with a smaller gear 13, both of said gears being positioned within the head 11. The gear 13 is rigidly mounted upon one end of a shaft 14, 55 upon the opposite end of which is rigidly mounted a sheave wheel 15. Positioned upon the sheave wheel 15 is a flexible element which is preferably a chain. As will be readily understood the wheel 15 may be rotated through the chain 16 and thereby rotation of the blower unit 10 is brought about.

In the operation of cleaners of this class the fluid most commonly used is steam. The head 11 is provided adjacent its under surface with an opening with which communicates a supply pipe 17 which communicates with a suitable source of supply of cleaning fluid. The head 11 is provided with a suitable opening 18 which communicates with the supply pipe 17. In this opening 18 is positioned one end of the blower unit or perforated pipe 10, permitting the blower unit to extend forwardly of the head 11 and into the interior of the boiler setting.

Formed in the rear of the head 11 is an opening 19 which communicates with the opening 18. Positioned in this opening 19 is a suitable piston head 20 provided with a shoulder or stud portion 20' to which is attached a valve 21. As shown in Figure 3, the valve 21 is surrounded by the opening 22 so that fluid entering the head through the pipe 17 is allowed to circulate around the entire valve. A spiral spring is positioned within the head, one end of said spring 23 resting against the piston head 20. The opposite end of said spring 23 engages a cap 24 which is secured to the head 11 by means of bolts 24' and serves as a closure for the opening 19. Piston rings 25 are positioned upon the piston head 20 and serve to prevent any escape of cleaning fluid around the piston head.

The piston head 20 is movable in the opening 19 and when moved to its forward position causes the valve 21 to rest upon a valve seat 26 and thereby closes communication between the opening 18 and the supply pipe 100.

17. This is the normal position of this valve, the spring 23 serving to retain the valve in its normally closed position. In order to open the valve it is apparent that the piston head 20 must be moved in the opening 19 so as to compress the spring 23.

Positioned within a pocket formed in the cap 24 is a valve 27 provided with a valve stem 28 which projects exteriorly of the cap 24. Formed in the head at one side there is 10 a passage-way 29 which communicates at one end with the opening 22 and at its opposite end with an opening 30 formed in the cap 24. This opening 30 communicates with 15 a passage-way 31 which opens into the pocket formed in the cap 24. A ball valve is provided in the open end of this passage-way 31 so as to close this end of this passage as will be readily understood. Formed in the cap 24, diametrically opposite the passage 31 is 20 an exhaust passage 34 which provides a connection between the pocket formed in the cap and the exterior of said cap. The valve 27 which is in the nature of a disc is positioned 25 in the pocket formed in the cap and is provided on its periphery with a pocket 33, communicating with which are peripheral bleed 30 passages 37. Formed in the valve 27 is an additional pocket 35 communicating with 35 which are bleed passages 36. It is to be noted that these bleed passages 36 terminate at a point which is substantially diametrically opposite to the pocket 33.

When the pocket 33 is in alignment with 35 the passage 31 the ball valve 32 serves as a closure for the passage 31, the ball 32 projecting into the pocket 33. When such a condition exists the bleed passages 36 will be in communication with the exhaust passage 34 and thereby the steam contained within the opening 19 will be exhausted. The pocket 35 communicates with open space 19 by means 40 of a forwardly projecting passage 35'. Upon turning the valve so that the ball valve 32 rides on the periphery of the valve 27, the 45 passage 31 is in communication with bleed passages 37 thereby allowing the steam to enter opening 19 through the pocket 33. The pocket 35 is then in alignment with the passage 34. The steam entering space 19 flows 50 through the passageway 35' and into the pocket 35 forcing the ball B, which is positioned in the pocket 35, against the end of the passage 34 so as to close the exhaust.

55 This is the normal position of the valve when the blower is not being operated. It is to be noted that when the valve 27 is in its normal position the steam from the supply pipe fills the opening 19 and the opening 60 22 so that pressure is exerted upon both sides of the piston head 20. When such is the case the spiral spring serves to assist the steam pressure to retain the valve 21 against the valve seat 26. When the valve is so positioned as to allow the ball 32 to project into

65 pocket 33 the bleed passages 36 communicate with the exhaust passage 34 and the steam contained in the opening 19 is allowed to escape. When such is the case the steam pressure from the pipe 17 is exerted on the forward side of the piston head 20 and forces the same rearwardly against the pressure of the spring 23. This opens communication between the pipe 17 and the blower unit 10.

To provide means for operating this valve so that steam or other cleaning fluid will be admitted to the blower unit during the rotating of the unit, a bar 38 is securely fastened to the head 11 by means of bolts 38'. To the opposite ends of this bar 38 is pivotally mounted a sleeve or guide member 39 and 75 39' respectively through each of which chain 16 projects after passing around or over the wheel 15. A stud projects forwardly from 80 each of said sleeves, said stud 40 being threaded at its end and projected through the member 38. A suitable nut 41 is provided for securing this threaded end in position relative to the bar 38. Rigidly attached at 85 one end to the member 39 is a link 42, the opposite end of which is pivoted to one end of a link 43, the opposite end of said link 43 being rigidly attached to the valve stem 28. Attached to the sleeve 39', at one end, is 90 a link 44, the opposite end of said link being pivotally secured to the link 43 at the point at which is attached the link 42, there being a longitudinal slot connection between the 95 links 42 and 43. It is apparent that upon 100 swinging the free ends of said sleeves so as to recede from each other the valve stem is caused to turn. It is also apparent that any downward strain exerted upon the depending end of chain 16 will cause the sleeves to 105 recede from each other at their free ends.

When the blower unit is to be rotated counter-clockwise in Figure 1, by rotating the sheave 15 clockwise in that figure, the 110 operator pulls on the right-hand part of the chain 16. The initial pull swings the sleeve 39 on its pivot 40 against the pressure of spring 45, because of the normal angular position of the sleeve in relation to the downwardly extending chain and because the resistance to rotation of the unit and therefore of the sheave 15 provides a temporary holding of the upper end of the chain 16. This 115 instantly causes valve 21 to be unseated by the pressure of the steam from the pipe 17 and consequently the steam flows into the blower unit. Continued pulling on the chain 16 rotates the sheave 15 and the unit. The parts preferably are proportioned so that the 120 sleeve 39 is vertical when the arm 43 and the valve 27 have been rotated to bring the space 19 into communication with the exhaust port 34, so that the chain may pass freely through the sleeve in a substantially straight line. Obviously, so long as the chain 16 is pulled, 125 130

the valve 21 will remain open because the sleeve 39 will be held in its vertical position.

If the unit is to be oscillated, instead of being continuously rotated in one direction, it will be obvious that the left-hand part of the chain 16 in Figure 1 must be pulled. If the right-hand part of the chain is released before the left-hand part is pulled, the spring 45 will return the parts to the position of Figure 1 and cause the valve 21 to close. As soon as pull is exerted on the left-hand part of the chain, however, the valve 21 will again be opened just before the unit begins its return rotation.

Obviously, if desired, this closing and opening of valve 21 between each change of direction of rotation of the unit may be avoided by holding the two parts of the chain 16 at all times under at least enough pressure to prevent the operation of the spring 45. Then as the pulling pressure is transferred from side to side of chain 16, the valve 21 will remain open.

It will also be noted that the valve 21 may be opened by merely swinging the right-hand part of the chain sidewise to the right in Figure 1 without pulling on it, this sidewise motion opening the valve 21 and then the chain may be pulled to rotate the unit. When so operated, however, the valve 21 will be opened before the unit begins to rotate, precisely as when the chain 16 is merely pulled downward. It will also be obvious that, because of the shifting of the position of the sleeve, the chain 16 is swung bodily to the right of Figure 1, even when the chain is pulled to start the operation. In other words, whether the chain is first swung to the right and then pulled, or whether the operator merely pulls on the chain, the parts are moved to the same position, the sleeve 39 swinging on its pivot and the chain moving to the right of Figure 1.

While I have illustrated and described the preferred form of construction for carrying my invention into effect, this is capable of variations and modifications without departing from the spirit of the invention. I therefore do not wish to be limited to the precise details of my invention, but desire to avail myself of such variations and modifications as come within the scope of the appended claims.

The foregoing is a continuation of my application No. 424,612, filed Nov. 17, 1920. In place of the structure above described, the structure disclosed in application Serial No. 612,766, filed Jan. 15, 1923, in which I am named as co-inventor with Norman L. Snow and Curtis L. Howse, may be used.

Describing first in detail the particular embodiment shown in Figures 7 and 8, A designates a rotatable blower pipe or blower unit having discharge nozzles B adapted for discharge of steam or the like therethrough

for cleaning the surfaces of the boiler tubes C or other surfaces to be cleaned.

The blower pipe A receives its steam through ports A', these ports communicating through the chamber A² with the stationary steam inlet B'. For closing the communication of ports A' with inlet B' there is provided a valve D adapted to engage a seat D'. The valve D is carried by the valve stem D² and is operated by turning the sheave or hand-wheel E in the following manner: This sheave wheel E is fixedly secured to the shaft F so that when the sheave wheel is revolved the shaft F also revolves.

Assuming that the valve D is against its seat D', the wheel E is revolved to the right. This also turns the worm G which is fixed on the shaft F. The worm G meshes with the worm gear G'. The latter, however, in this position of the parts is prevented from revolving due to the fact that it is held by the dog H which engages a slot H' in the worm gear hub. The continued operation of revolving the wheel E to the right results in the wheel E, shaft F and worm G being moved forward as the shaft F carries the valve stem D², in opening the valve D from its seat D'. When, however, the shoulder F' on the worm G abuts against the inner face F² of the worm gear housing this prevents further movement longitudinally of the worm and the valve. However, the proportion of parts is such that at this time the dog H has become disengaged from the slot H'.

The mechanism for disengaging the dog consists of a lever H² pivoted at H³ and having a projecting end H⁴ extending into a slot E². As the shaft F is fed forward the shoulder of the slot E² will force the projecting end H⁴ of the lever H² forwardly and thus rock the locking dog H to a position where it will clear the slot H'. Further rotation of the handle E to the right will then revolve the worm gear G', the locking dog H being held out during the further rotation of the wheel E. The blower is then reversed by turning the wheel E in the left-hand direction but the shaft F cannot move longitudinally due to the fact that it is held in by the dog H riding on the surface of the hub H⁵. The blower pipe will then be revolved in the left-hand direction until the slot H' comes back into registration with the dog H.

When this registration of the dog H and the slot H' again takes place the dog comes in contact with the lug E⁴ which holds the blower pipe from further rotation and immediately the stem F starts to move to the right and continues this movement until the valve D is brought tightly against the seat D'. It will be noticed that this novel arrangement is not only used for rotating the unit and adjusting the valve but that the unit is positively held from rotation both during the opening and closing of the valve.

It is, of course, understood that the valve could just as readily be one that is forced against its seat as one that is drawn against its seat.

5 The same broad idea of locking the unit from rotating automatically while the valve is being opened and closed from the same operating member is embodied in the construction shown in Figures 9, 10 and 11.

10 Describing more in detail this modified form, J designates the stationary supply pipe which through the passage J' and port J² connects to the interior of the valve cage. The length of the periods of admission of 15 steam to the interior of the valve cage J⁴ is controlled by a plate J³ which can be adjusted for the various installations right at the place of installation by cutting off a portion of the plate to secure the desired opening in the port or slot. The actual admission 20 of steam to the blower unit is, however, controlled by a valve K carried by the rotating shaft K'.

On the outer end the shaft K' is provided 25 with screw threads K² upon which there is loosely threaded the sheave wheel L. The latter carries a set of combination thrust and radial ball bearings L' which prevent the sheave from moving in and out. The shaft 30 K' is also provided with four grooves M. Cooperating with these grooves in the manner hereinafter described and mounted in a suitable housing M' carried by a stationary part of the blower structure, are locking 35 dogs M' and M² normally pressed toward the grooves by springs M³ and M⁴. The dog M' is provided with a groove engaging portion M⁶. It will be noted that the groove engaging portions M⁶ and M⁶ are out of alignment 40 so that the groove engaging portion M⁶ will come to the end of its groove in advance of the groove engaging portion M⁶ when the shaft is moved toward the left. For steady- 45 ing the dogs M' and M², suitable members M⁸ may be threaded through the housings M' for engagement in grooves M⁹ formed in the dogs. For opening the valve the sheave wheel L is revolved in the right-hand direction. However, in this position the locking 50 dog M² fitting in one of the slots M will prevent the shaft K' from rotating. The sheave L through the screw threads K² will then act as a nut to feed the shaft K' outward which will result in moving the valve K away 55 from its seat K³. This opening movement will continue until the dog M² reaches the incline N where it starts to rise out of the groove and finally rests on the outer surface of the shaft K'. In this position the shaft K' 60 is free to revolve and at the same time the shoulder O on the shaft K' comes into contact with the shoulder O' on the sheave wheel preventing the screw and shaft K' from running any further outward. In effect that 65 locks the sheave L and shaft K' together

as the sheave L continues to be rotated in a right-hand direction.

After the shaft K' is free to revolve the continued movement in the right-hand direction of the sheave L will rotate the blower 70 pipe Q so as to properly direct the steam from its jets Q' against the surfaces of the boiler tubes R or at the surfaces to be cleaned. Vanes or splines S on the shaft are provided so that a longitudinal movement can take 75 place between the shaft K', the driver part T and the valve cage J⁴. After revolving the blower pipe through the desired arc of rotation, the sheave wheel is then revolved in a left-hand direction. When the wheel is ro- 80 tated in a left-hand direction the shaft K' is locked from rotation by the engagement of dog M' in one of the slots M. Continued rotation of the sheave wheel L in a left-hand direction will then feed the threaded portion or worm K² of the shaft inward, moving the shaft K' and the valve K until the latter is finally seated against its seat K³. In this last described construction it will be noted that the right-hand movement only of the 85 sheave wheel is utilized for rotating the unit whereas in the construction shown in Figures 7 and 8 the initial right-hand movement opens the valve and the continued right-hand move- 90 ment of the wheel rotates the unit and it is then rotated back during the initial left-hand rotation of the wheel. In each of the last two described constructions, however, it will be noted that the unit is locked from rotation while the valve is being opened and 95 closed so that a positive mechanical operation of the valve takes place which cannot be effected by steam pressure or other factors. 100

For the sake of convenience the invention has been described as being embodied in a 105 boiler cleaner for cleaning parts of a boiler. It will be apparent, however, that the invention may be embodied in any similar cleaning device, and it is to be therefore understood that the term "boiler" wherever used throughout the specification and claims is to be construed as meaning a fluid heater or heat transfer apparatus of any character while the term "boiler cleaner" is to be construed as meaning a cleaner for any such apparatus. 110

In this application no claims are directed to the specific structure shown in Figures 7 to 11, inclusive, since this specific structure is claimed in the said application, Serial No. 612,766, filed Jan. 15, 1923, in which application I am named as co-inventor with Norman L. Snow and Curtis L. Howse. Claims to the broad subject matter of these figures, however, are included in this application as well as claims specific to the structure shown 115 in Figures 1 to 6, inclusive.

It might be further noted that in this application no claims are directed to the mechanism providing for utilization of the cleaning fluid to effect an actuation of the valve, 120

claims to this feature being incorporated in my co-pending divisional application Serial No. 348,093, filed March 18, 1929.

While several forms of the inventive idea have been disclosed in this application, it is to be understood that the description is illustrative only and is not definitive of the limits of the inventive idea. The right is reserved to make such changes in the details of construction and arrangement of parts as will fall within the purview of the attached claims.

What I claim as my invention is:

1. A boiler cleaner comprising a rotatable blower unit, means for rotating said unit, means for supplying a cleaning fluid to said unit, means for controlling the supply of said fluid, operating means for said control means, guide members connected to said operating means, and a flexible member projecting through said guide members and adapted for actuating said rotating means and said control operating means.

2. A boiler cleaner comprising a rotatable blower unit, means for rotating said unit, means for supplying a cleaning fluid to said unit, means for controlling the supply of said fluid to said unit, a flexible member for actuating said rotating means, guide members for said flexible member, and means connected to said guide members operable through tension exerted on said flexible member for operating said control means.

3. In a boiler cleaner, the combination with a rotatable blower unit adapted to discharge jets of cleaning fluid, of a valve for controlling the supply of cleaning fluid to said unit, a power-transmitting member, and means receiving motion from said power-transmitting member only to first cause said valve to be moved to open position to supply cleaning fluid to said unit while said unit is at rest and then rotate said unit, said means being arranged to complete the operation of the valve and the unit in the order named.

4. In a boiler cleaner, the combination with a rotatable blower unit adapted to discharge jets of cleaning fluid, of a valve for controlling the supply of cleaning fluid to said unit, a power-transmitting member, and means receiving motion from said power-transmitting member only, to first actuate said valve to supply cleaning fluid to said unit while said unit is at rest and then to rotate said unit, said means being arranged to normally prevent the transmission of motion from said member to said unit before said valve is actuated.

5. In a boiler cleaner, the combination with a rotatable blower unit adapted to discharge jets of cleaning fluid, of a valve for controlling the supply of cleaning fluid to said unit, a power-transmitting member, and means, including connections between said member and said valve and between said member and

said unit, to first actuate said valve to supply cleaning fluid to said unit while said unit is at rest and then to rotate said unit, said valve being operatively connected to said member while the unit is rotating.

6. In a boiler cleaner, the combination with a rotatable blower unit adapted to discharge jets of cleaning fluid, of a valve for controlling the supply of cleaning fluid to said unit, a normally-stationary power-transmitting member, and means receiving motion from said member only to first actuate said valve to supply cleaning fluid to said unit when said member starts from rest and while said unit is at rest and then to rotate said unit and to compel the operation of the valve and the unit in the order named.

7. In a boiler cleaner, the combination with a rotatable blower unit adapted to discharge jets of cleaning fluid, of a valve for controlling the supply of cleaning fluid to said unit, a normally-stationary power-transmitting member, and means, receiving motion from said member only, to first actuate said valve to supply cleaning fluid to said unit when said member starts from rest while said unit is at rest and then to rotate said unit, and to compel the operation of the valve and the unit in the order named, said means maintaining the valve in actuated position while the unit is rotating.

8. In a boiler cleaner, the combination with a rotatable blower unit adapted to discharge jets of cleaning fluid, of a valve for controlling the supply of cleaning fluid to said unit, a power-transmitting member, a bodily-movable element arranged to be moved by said member, connections between said element and said valve to actuate said valve to supply cleaning fluid to said element, and connections between said member and said unit to rotate said unit, said member and said first-named connections being adapted to maintain said valve in actuated position while the unit is rotating.

9. In a boiler cleaner, the combination with a rotatable blower unit adapted to discharge jets of cleaning fluid, of a valve for controlling the supply of cleaning fluid to said unit, a power-transmitting member, means operated by movement of the power-transmitting member for actuating the valve, and means automatically brought into operation by movement of the same power-transmitting member for rotating the unit after the first-mentioned means has been actuated.

10. In a boiler cleaner, the combination with a rotatable blower unit adapted to discharge jets of cleaning fluid, of a valve for controlling the supply of cleaning fluid to said unit, a normally-stationary power-transmitting member, means brought into operation by the initial movement of said power-transmitting member for actuating the valve, and means automatically brought into opera-

tion by further movement of the same power-transmitting member for rotating the unit.

11. In a boiler cleaner, the combination with a rotatable blower unit adapted to discharge jets of cleaning fluid, of a valve for controlling the supply of cleaning fluid to said unit, valve-actuating mechanism, including a bodily movable sleeve, unit-rotating mechanism to rotate said unit, and a normally-stationary, power-transmitting member to actuate both of said mechanisms and extending through said sleeve, said power-transmitting member and said mechanisms being constructed and arranged so that motion of said power-transmitting member from rest first moves said bodily movable sleeve to actuate said valve, and then actuates said unit-rotating mechanism, said power-transmitting member and sleeve moving bodily relatively to each other while the unit is rotating.

12. In a boiler cleaner, the combination with a rotatable blower unit adapted to discharge jets of cleaning fluid, of a valve for controlling the supply of cleaning fluid to said unit, a power-transmitting member, connections between said member and said valve adapted to actuate said valve when said member is moved, connections between said member and said unit to transmit power from said member to rotate said unit, said last-named connections and said unit being arranged not to receive the motion of said power-transmitting member until said first-named connections have been moved to operate said valve.

13. In a boiler cleaner, the combination with a rotatable blower unit adapted to discharge jets of cleaning fluid, of a valve for controlling the supply of cleaning fluid to said unit, a power-transmitting member mounted for motion in at least two directions, and connected at all times to said unit, whereby said unit may be rotated by said member when moved in one direction, and means operated by motion of said member in another direction to actuate said valve.

14. In a soot blower, the combination of a steam casing provided with a valve for controlling the passage of steam therethrough, a blower tube projecting from said casing to receive steam therefrom and having one end turnably mounted therein, said tube being provided with a discharge orifice, and manually operable means for operating said valve and tube, said means being arranged to operate said valve in advance of said tube.

15. In a soot blower, the combination with a rotatable blower unit adapted to discharge a jet of cleaning fluid, of a valve for controlling the supply of cleaning fluid to said unit, a power-transmitting member, and mechanism actuated by said power-transmitting member to first actuate said valve to supply cleaning fluid to said unit and to then rotate

said unit upon further movement of said power-transmitting member.

16. In a soot blower, the combination with a blower unit and a valve for controlling the supply of cleaning fluid to said unit, of an actuating member and means automatically controlled by the movement of said actuating member for successively actuating said valve and rotating said blower unit.

17. A boiler cleaner comprising a rotatable blower unit adapted to discharge a jet of cleaning fluid, a conduit for supplying cleaning fluid to said blower unit, a valve for controlling the supply of cleaning fluid through said conduit to the blower unit, means for rotating said blower unit, a flexible member for actuating said rotating means, a member connected to actuate said valve and projecting in the path of the said flexible member, and means operable through a tension exerted on the flexible member for imparting movement from the flexible member to said valve actuating member for actuating the valve.

18. In a soot blower, the combination with a blower unit and a valve for controlling the supply of cleaning fluid to said unit, of an actuating member, and means automatically controlled by the movement of said actuating member successively moving said valve to substantially open position and rotating said blower unit.

19. A soot cleaner comprising a rotary cleaner element, an enclosed valve for controlling admission of steam thereto, and means for operating said cleaner element and valve, said means being arranged to successively open the valve and rotate the element.

20. In a soot blower, the combination with a rotatable blower pipe, a valve for controlling the supply of cleaning fluid to said pipe and means for actuating said valve, of a common means for rotating said pipe and actuating said valve actuating means, said common means consisting of a member adapted upon one movement to actuate said valve actuating means and upon a second movement to rotate said blower pipe, and means normally preventing the second movement until the first movement has been completed.

21. In a boiler cleaner, the combination with a blower element, of a valve for controlling the passage of cleaning fluid therethrough, the said valve being operable prior to movement of the blower element, and a single means having one type of movement for operating said valve and an independent type of movement for operating said blower element, whereby said valve and blower element may be successively operated.

22. The combination with a blower element and a valve for controlling the supply of cleaning fluid to said element, of means for actuating said valve, means for moving said blower element, a member mounted for two types of movement and so arranged with re-

5 spect to both of said means that when one type of movement is imparted to the member one of said means is actuated and when movement of the other type is imparted to the member the other means is actuated, and means for causing said two types of movement to be successively imparted to said member upon actuation thereof to effect a successive actuation of the said means.

10 23. In a boiler cleaner, the combination with a blower element, and a valve for controlling the passage of cleaning fluid through said blower element, of mechanism for successively operating said valve and moving said blower element, said mechanism including a member mounted for two different types of movement, movement of said member conformable to one type effecting an operation of said valve and movement of said member conformable to the other type effecting a movement of said blower element.

15 24. In a boiler cleaner, the combination with a movable blower element and a valve for controlling the flow of cleaning fluid to said blower element, of an actuating member mounted for two different types of movement, said actuating member being so arranged with respect to means for actuating said valve and blower element that movement of said actuating member conformable to one type effects an actuation of said valve and movement of said actuating member conformable to the other type effects a movement of said blower element, and means normally compelling movement of said actuating member conformable to one type in advance of movement of the actuating member conformable to the other type whereby said valve is actuated prior to movement of said blower element.

20 25. In a boiler cleaner, the combination with a movable blower element and a valve for controlling the flow of cleaning fluid to said blower element, of an actuating member mounted for two different type of movement, said actuating member being so arranged that movement thereof conformable to one type effects an actuation of said valve and movement thereof conformable to the other type effects a movement of said blower element, and means operable upon actuation of said actuating member to cause the same to open said valve prior to the movement of the blower element and to close the said valve upon completion of the movement of the blower element.

25 26. In a boiler cleaner, the combination with a rotatable blower element, means for rotating said element, and a valve axially aligned with said blower element for controlling the passage of cleaning fluid to said element, of means cooperating with said element rotating means for axially moving said valve to open and close the same, said last mentioned means being arranged to open

said valve prior to the rotation of said blower and to close said valve upon completion of the rotation of said blower element.

30 27. In a boiler cleaner, the combination with a movable blower element adapted to discharge steam or the like, and a valve for controlling the admission of steam or the like to said blower element, of a flexible operating member, a connection between said flexible member and said blower element arranged to move the latter from the former and a member cooperating with said flexible member controlling the actuation of said valve said member being independent of said connection.

35 28. In a boiler cleaner, the combination with a movable blower element, of a valve controlling the admission of steam or the like to said blower element, a flexible member for moving said blower element, and means associated with said valve and flexible member for actuating the former from the latter, said last mentioned means being arranged to actuate said valve prior to movement of said blower element.

40 29. In a boiler cleaner, a rotatable blower pipe, a valve for controlling the flow of cleaning fluid to said pipe, means including a flexible member for rotating said blower pipe, and means operable upon the exertion of a pull on said flexible member and prior to the rotation of said blower pipe by said flexible member to effect an opening of said valve.

45 30. In a boiler cleaner, a movable blower element, a valve for controlling the flow of cleaning fluid to said blower element, means including a flexible member for moving said blower element, means associated with said flexible member and operable upon the exertion of a pull thereon to effect an opening of said valve, and means operable upon the release of said flexible member to effect a closing of said valve.

50 31. In a soot blower for boilers, a rotatable blower element, a steam supply pipe therefor, a valve for controlling the supply of steam to the blower element, means for rotating the blower element, means for opening said valve, a driving element for actuating the valve-opening means, and means for automatically effecting an actuation of said blower rotating means by a continued actuation of said driving element after said driving element has been moved to operate the valve-opening means.

55 32. In a soot blower, the combination with a blower tube and a valve for controlling the supply of cleaning fluid to said tube, of means for moving said valve to a predetermined position, and means for causing continued operation of said means thereafter automatically to move the blower tube.

60 33. In a boiler cleaner, a movable blower element, a valve for controlling the flow of cleaning fluid to the blower element, means

- for moving said blower element, and means operable upon actuation of said blower element moving means to effect an opening of said valve prior to the movement of said blower element.
34. In a boiler cleaner, a movable blower element, a valve for controlling the flow of cleaning fluid to said blower element, means for moving said blower element, means operable upon actuation of said blower element moving means to effect an opening of said valve prior to the movement of said blower element, and means operable upon discontinuance of the actuation of said blower element moving means to effect a closing of said valve.
35. In a boiler cleaner, a movable blower element, a valve controlling the flow of cleaning fluid to said blower element, means for moving said blower element, and means automatically operable to compel opening of said valve prior to movement of said blower element whereby said valve is always open during movement of said blower element.
36. In a boiler cleaner, a rotatable blower element, a valve controlling the flow of cleaning fluid to the blower element, means including a flexible member for rotating said blower element, means operable upon the exertion of a pull on said flexible member incident to the rotation of the blower element to open the valve, and means operable upon release of said flexible member to effect a closing of said valve.
37. In combination, a blower element mounted for unlimited movement in two directions, means for moving said element in the said two directions, a valve for controlling the flow of cleaning fluid to said element, and means operating upon actuation of said blower element moving means incident to movement of said blower element in one of said directions to effect an opening of said valve and to hold said valve open during continued movement of said blower element in the said direction.
38. In combination, a blower element mounted for unlimited movement in two directions, means for moving said element in the said two directions, a valve for controlling the flow of cleaning fluid to said element, and means operating upon actuation of said blower element moving means incident to movement of said blower element in either of said directions to effect an opening of said valve and to hold said valve open during the continued movement of said blower element in either of the said directions.
39. In combination, a blower element mounted for unlimited rotation, means for rotating said blower element, a valve for controlling the flow of cleaning fluid to said element, and means operating upon actuation of said blower element rotating means incident to rotation of said blower element in one direction to open said valve and to hold said valve open during the continued rotation of the said blower element in the said direction.
40. In combination, a blower element mounted for unlimited rotation, means for rotating said blower element, a valve for controlling the flow of cleaning fluid to said blower element, and means operating upon actuation of said blower element rotating means to effect an opening of said valve and to hold said valve open during continued rotation of said blower element.
41. In combination, a blower element mounted for unlimited movement in two directions, means for moving said element in the said two directions, a valve for controlling the flow of cleaning fluid to said element, and means operating to effect an opening of said valve prior to movement of the said blower element in either of said directions and to hold said valve open during the continued movement of said blower element in either of said directions.
42. In combination, a blower element mounted for unlimited rotation, means for rotating said blower element, a valve for controlling the flow of cleaning fluid to said element, and means operating to effect an opening of said valve prior to rotation of said element and to hold said valve open during the continued rotation of said element.
43. In a boiler cleaner, a blower movable to direct a jet of cleaning fluid adjacent portions of a boiler to be cleaned, and a member mounted for two types of movement for controlling the flow of cleaning fluid to said blower and for moving said blower, movement of said member conformable to one type controlling the flow of cleaning fluid to said blower, and movement of said member conformable to the other type effecting a movement of said blower to direct the cleaning fluid discharged therefrom adjacent portions of the boiler to be cleaned.
44. In a boiler cleaner, a rotatable blower, a cleaning fluid supply pipe, and a member mounted for two types of movement for controlling the flow of cleaning fluid from said supply pipe to said blower and for rotating said blower, movement of said member conformable to one type controlling the flow of cleaning fluid from said supply pipe to said blower and movement of said member conformable to the other type effecting a rotation of said blower.
45. In a boiler cleaner, the combination with a blower element and a source of cleaning fluid, of a valve controlling the supply of cleaning fluid from said source to the blower element, a member adapted to control said valve, a second member adapted to rotate the blower element, an actuating mem-

ber, and means operating upon actuation of the actuating member to cause the said actuating member to act successively on the said first mentioned members for causing the 5 valve and blower element to function.

46. In a boiler cleaner, a rotatable blower element, means for oscillating said blower element, a valve controlling the flow of cleaning fluid to the said blower element, and means 10 operating upon actuation of said blower element oscillating means to actuate said valve, said last mentioned means being arranged to provide for opening and closing said valve when the blower element is at one end of its 15 arc of oscillation and for holding the valve open when the blower element is at the other end of its arc of oscillation, said last-mentioned means being also arranged to cause said valve to open prior to movement of the 20 blower element.

47. In a boiler cleaner, the combination with a rotatable blower element, means for rotating said element, and a valve axially aligned with said blower element for controlling the passage of cleaning fluid to said element, said valve including a valve seat member defining a port coaxial with said blower element and a valve member engageable with said valve seat member, of means operating 25 upon actuation of said blower element rotating means to effect a relative movement between said members to admit cleaning fluid to the blower element prior to rotation of said blower element by said rotating means.

48. In a boiler cleaner, the combination with a rotatable blower element, means for rotating said blower element, a valve including a valve seat member defining a port coaxial with said blower element, and a valve 30 member cooperating with said valve seat member for controlling the flow of cleaning fluid to said blower element, of means operating upon actuation of said blower element rotating means to effect a relative movement 35 between said valve member and said valve seat member in the direction of the axis of said blower element to admit cleaning fluid to the blower element prior to rotation of said blower element by said rotating means.

49. In a boiler cleaner, the combination with a rotatable blower element, means for rotating said blower element, and a valve axially aligned with said blower element for controlling the passage of cleaning fluid to said element, said valve including a valve member and a valve seat member, of means 50 cooperating with said blower element rotating means for effecting a relative movement between said members for admitting cleaning fluid to the said blower element said last recited means being arranged to admit cleaning fluid to the blower element prior to rotation thereof by said rotating means.

50. In a fluid heater cleaner, a blower element mounted for unlimited oscillation, a

valve for controlling the admission of cleaning fluid to said blower element, means for actuating said valve, means for oscillating said blower element, and a single actuating member for effecting an operation of the 50 valve actuating means and actuation of the blower element oscillating means, said single member when operated so controlling the operation of the valve operating means and the blower element oscillating means that the 55 blower element does not oscillate until an actuation of the valve has been effected.

In testimony whereof I affix my signature.
FRANK BOWERS.
